UNITED STATES PATENT OFFICE.

JOHN HAYS HAMMOND, JR., OF GLOUCESTER, MASSACHUSETTS.

ELECTRORADIANT SIREN.

Application filed July 13, 1914, Serial No. 850,621. Renewed July 24, 1923.

To all whom it may concern:

Be it known that I, JOHN HAYS HAMMOND, Jr., a citizen of the United States, and a resident of Gloucester, in the county of Essex and State of Massachusetts, have invented an Improvement in Electroradiant Sirens, of which the following description, in connection with the accompanying drawings, is a specification, like characters on the drawings representing like parts.

Some of the objects of this invention are to provide means for emitting electro-radiant energy in the form of siren waves; to provide means for automatically emitting electro-radiant energy in the form of siren waves; to provide means for automatically emitting electro-radiant energy in the form of siren waves in combination with means to modify the action of the transmission means to cause the same to emit waves of a constant frequency; and to provide other improvements as will appear hereinafter.

The accompanying drawing shows diagrammatically one form of wave siren constructed in accordance with this invention.

Referring to the drawing, one embodiment of this invention comprises an alternator, or other suitable source of energy 1 in circuit with the primary 2 of a transformer, 80 of which the secondary is indicated at 3 as in a closed oscillatory circuit 4, having a suitable condenser 5, spark gap 6 and primary 7 of a transformer, the secondary whereof is indicated at 8 as forming part of 85 the aerial or antenna 9. The oscillatory circuit 4 is in series by means of a conductor 10 with an inductance 11, in co-acting relation with which is a switch 12 preferably continuously rotated by any suitable means (not 90 shown), so as to vary the amount of inductance thereby thrown into the oscillatory circuit 4. Leading from the switch 12 is a conductor 13 having a switch 14 adapted to make suitable contact with a terminal 15. Mounted 95 in suitable relation to the switch 14 is an electromagnet 16, and connected to one end of the coil of this magnet 16 is a conductor 17 leading to ground at 18. So long as the switch 14 is open, the inductance 11 or a portion 100 thereof is in series with the inductance 7 of the oscillatory circuit 4; that is, a circuit exists through the inductance 7, the inductance 11, the switch 12, the condenser 5 and the spark gap 6. When, however, the magnet 16 is energized, the switch 14 is closed, and the entire inductance 11 is short 105

circuited and will therefore have no effect upon and will not be included in the described circuit.

The aerial or antenna 9 is provided with a conductor 19 having a suitable inductance 20 in operative relation to which is a switch 21 adapted to be preferably continuously rotated by any suitable means (not shown).

Leading from the rotary switch 21 is a conductor 22 having a terminal 23 and also leading to the ground 24. Pivoted to swing into and out of engagement with the terminal 23 is a switch 25 which is normally held open or out of engagement with the terminal 23 by means of a spiral spring 26. This switch 25 is connected to the conductor 19 by a branch conductor 27 and is arranged to form an armature for and to be controlled by a fixed electro-magnet 28. One end of the coil of the electro-magnet 28 is grounded as at 18 through a conductor 29, the coil of the electro-magnet 16, and the conductor 17. The other end of the coil of the electro-magnet 28 is grounded as at 30 through a conductor 31 containing a battery 32 and arranged to be controlled by a manually operated switch 33.

As long as the switch 33 remains open, the switch 25 will remain open and the aerial or antenna 9 will be grounded as at 24 through the inductance 8, the conductor 19, a variable part of the coil 20, the rotary switch 21 and the conductor 22. When, however, the switch 33 is closed, thus energizing the magnet 28 and closing the switch 25, the entire inductance 20 will be short-circuited, and the aerial 9 will be grounded as at 24 through the inductance 8, the conductor 19, the branch conductor 27, the switch 25, the terminal 23, and the conductor 22. Also, when the switch 33 is open, the electro-magnet 16 will be deenergized and consequently the switch 14 will remain open and the primary coil 7 will be in series with the conductor 10, a variable portion of the coil 11, the rotary switch 12, the conductor 13 and the secondary coil 3, but when the switch 33 is closed, the electro-magnet 16 will be energized thus causing the switch 14 to engage against the contact 15 and thus short-circuit the entire coil 11 and connect the primary coil 7 directly in series with the secondary coil 3.

In the operation of this improved system, the switch 33 is normally left open and the switches 12 and 21 are normally rotated in unison thereby simultaneously causing a con-

stant variation in the effective lengths of the two coils 11 and 20 which are in series respectively with the primary and secondary coils 7 and 8. The two coils 11 and 20 and the two rotary switches 12 and 21 are so arranged and proportioned that while the switch 33 is open and the two rotary switches 12 and 21 are in operation, the closed oscillatory circuit including the primary coil 7 and a variable portion of the coil 11 will always be maintained in resonance with the open aerial circuit including the secondary coil 8 and the variable portion of the coil 20 and the open aerial circuit 9 will be caused to emit electro-radiant waves which will be constantly varied in frequency and consequently in wave length between predetermined limits, the variations in frequency occurring in periodic cycles in each of which the frequency is varied step by step through a large number of small steps from a predetermined given frequency to a predetermined second frequency. When the coils 11 and 20 are short-circuited by closing the switch 33, as hereinbefore described, the open aerial circuit 9 will be caused to emit electro-radiant waves having a predetermined frequency and a corresponding wave length, for instance having a frequency which will give a wave length of approximately 3000 meters.

Although only a single form has been shown herein in which this invention may be embodied it is to be understood that the invention is not limited to any specific construction but might be applied in various

forms without departing from the spirit of the invention or the scope of the appended claims.

Claims:

1. The combination with means for transmitting radiant energy in the form of siren waves, comprising an open aerial circuit, a closed oscillatory circuit, a pair of elements arranged to be moved continuously to simultaneously vary the electrical values of said circuits respectively to maintain said circuits in resonance, and means for simultaneously short circuiting said elements to render said elements ineffective while moving to vary the electrical values of said circuits. 40
2. The combination with means for transmitting radiant energy in the form of siren waves, comprising an open aerial circuit, a closed oscillatory circuit, a pair of elements arranged to be rotated continuously to simultaneously vary the electrical values of said circuits respectively to maintain said circuits in resonance, and means for simultaneously short circuiting said elements to render said elements ineffective while moving to vary the electrical values of said circuits. 50

In testimony whereof, I have signed my name to this specification, in the presence of two subscribing witnesses.

JOHN HAYS HAMMOND, JR.
